[57] CLAIM

The ornamental design for a calculator with advertising spaces for shopping cart handle, as shown and described.

DESCRIPTION

FIG. 1 is a front view of a calculator with advertising spaces for shopping cart handle, showing my new design;

FIG. 2 is a left side view;

FIG. 3 is a right side view;

FIG. 4 is a bottom view;

FIG. 5 is a top view;

FIG. 6 is a rear view;

FIG. 7 is a left side view of a second embodiment of my new design, the front view thereof being identical to that of FIG. 1;

FIG. 8 is a right side view of the second embodiment;

FIG. 9 is a bottom view of the second embodiment;

FIG. 10 is a top view of the second embodiment;

FIG. 11 is a rear view of the second embodiment;

FIG. 12 is a front view of a third embodiment of my new design;

FIG. 13 is a left side view of the third embodiment;

FIG. 14 is a right side view of the third alternate embodiment;

FIG. 15 is a bottom view of the third alternate embodiment;

FIG. 16 is a top view of the third alternate embodiment;

FIG. 17 is a rear view of the third alternate embodiment;

FIG. 18 is a left side view of a fourth embodiment of my new design, the front view thereof being identical to that of FIG. 12;

FIG. 19 is a right side view of the fourth embodiment;

FIG. 20 is a bottom view of the fourth alternate embodiment;

FIG. 21 is a top view of the fourth alternate embodiment;

FIG. 22 is a rear view of the fourth alternate embodiment; and,

FIG. 23 is a perspective view of the embodiment of FIG. 1.
